(57) **CLAIM**

The ornamental design for a food container assembly, as shown and described.

DESCRIPTION

FIG. 1 is a front perspective view of the food container assembly embodying our design;

FIG. 2 is top plan view of FIG. 1, the arrows A through D showing the direction of the views of FIGS. 4 through 7;

FIG. 3 is a bottom plan view of FIG. 1;

FIG. 4 is a side elevational view from arrow A in FIG. 2;

FIG. 5 is a side elevational view from arrow B in FIG. 2;

FIG. 6 is a side elevational view from arrow C in FIG. 2;

FIG. 7 is a side elevational view from arrow D in FIG. 2;

FIG. 8 is a top perspective exploded view of FIG. 1 showing the component parts of the assembly;

FIG. 9 is a bottom perspective exploded view of FIG. 1 showing the component parts of the assembly; and,

FIG. 10 is an exploded side elevational view, in partial cross-section, of FIG. 1.
